APPARATUS FOR REMOVING OIL FROM THE IGNITION ELECTRODES OF OIL BURNERS

Joseph A. Logan, Hadley, Mass., assignor to Gilbert & Barker Manufacturing Company, West Springfield, Mass., a corporation of Massachusetts

Application April 18, 1951, Serial No. 221,547

1 Claim. (Cl. 236—46)

1

This invention relates to improvements in electrically-ignited oil burners, such for example as are adapted for house-heating service, and, more particularly, to the maintenance of the ignition electrodes clean and free from oil.

The ignition electrodes are usually mounted above the oil-atomizing nozzle with their tips close to but out of the direct path of the cone-like spray which is emitted from the nozzle. The arc-like spark, produced between the tips of the electrodes, is distended by the blast of air from the fan of the burner and forced into the spray to vaporize and ignite the same. There is, however, an area adjacent the conical spray where very fine mist of oil or vapor exists and because of this, the electrodes may, at the end of a run of the burner, have a thin film of oil thereon. Also, after the oil cut-off valve has closed, there may be a few drops of oil emitted from the nozzle and these will vaporize and some of the vapor may lodge on the electrodes.

This invention has for its object the provision in an electrically-ignited oil burner, of means for prolonging the ignition spark, after the motor, which drives the air-supply fan and oil-supply pump, has stopped, for the purpose of removing from the electrodes any oil that may have been deposited thereon, such removal being effected by the heat of the spark and immediately following each run of the burner, so that the electrodes are left dry and less apt to accumulate dirt.

Illustrative examples of the invention are shown in the accompanying drawings, in which:

Fig. 1 is a sectional plan view of a gun-type oil burner with which the invention may be employed;

Fig. 2 is an electrical diagram showing a burner control system embodying the invention; and

Fig. 3 is a fragmentary diagrammatical view illustrative of a modification.

Referring to these drawings: there is shown in Fig. 1, by way of illustrative example, one type of oil burner with which the improvements of this invention may be used. This burner is of the familiar gun type, used largely for house-heating service. It includes a fan 1, mounted on a housing 2 and supplying the air for combustion through a tube 3, near the outlet end of which is mounted a nozzle 4, herein indicated as of the pressure or mechanical atomizing type. The fan 1 is driven by an electric motor 5, which also drives an oil pump 6 but preferably through a suitable speed-responsive clutch 7, such for example as shown in my Patent No. 1,985,934, granted January 1, 1935, whereby the starting of the pump is delayed until the motor and fan have acquired considerable speed. The pump 6 may, for example, be of the type shown in Osborne Patent No. 2,233,709, granted March 4, 1941, such pump being incorporated with the usual filter, cut-off and pressure-regulating

valves in one casing forming a fuel-feeding unit. The inlet to this unit is adapted to be connected by a pipe 7' to a supply tank or liquid fuel and the outlet of the unit is connected by a pipe 8 to the atomizing nozzle 4. Ignition electrodes 9 are suitably mounted in tube 3 in igniting relation to the spray of oil emitted from the nozzle 4. The burner described represents one example of many burners with which the improvements of this invention may be used.

A burner of this type is usually controlled by a thermostat switch, which responds to room temperature and closes on a demand for heat from the burner and opens when the demand is satisfied. A typical control system for the burner is shown in Fig. 2. The room thermostat switch consists of a bi-metallic blade 10 and two stationary contacts 11 and 12, which are adapted to be successively engaged in the order named on a demand for heat from the burner. The thermostat may also include an electric heating coil 13, which is brought into play near the end of each run of the burner to accelerate the opening of the thermostat switch, when the demand for heat is satisfied. This switch controls a relay which in turn controls the motor 5 and the ignition means. The coil 14 of this relay is arranged in series with a time switch 15, an electric heating coil 16 associated with the time switch and two pairs of engaged contacts 17 and 18, in a low voltage starting circuit which is supplied from the secondary 19 of a step down transformer 20. The primary 21 of this transformer is connected by wires 22 and 23 to terminals 24 and 25, respectively, which are adapted for connection to a suitable source of electricity exemplified by the line wires 26 and 27 of a 115 volt, 60 cycle, alternating current supply. The secondary 19 may, for example, supply current at 24 volts. The starting circuit may be traced as follows: from the right hand terminal of secondary 19 by a wire 28, terminal 29 and wire 30 to contact 11, thence by blade 10, contact 12, wire 31, terminal 32, wires 33 and 34, engaged contacts 18 and 17, wire 35, heating coil 16, closed switch 15 and wire 36 to coil 14 and thence by a wire 37 to the other terminal of secondary 19. On closure of this starting circuit, the coil 14 will be energized and a series of switches 38, 39, 40, 41 and 42 will be simultaneously closed. Closure of switch 38 will close a circuit to motor 5 which circuit may be traced as follows: from wire 26 by terminal 24, wire 43, closed switch 38, wire 44, terminal 45 and wire 46 to one terminal of motor 5 and thence from the other terminal of the latter by wire 47 and terminal 25 to the other line wire 27. Ordinarily, the ignition circuit would also be closed by the same switch used to start the motor 5 but, for reasons later to appear, a separate switch 39 is used for the purpose. The ignition means consists of a step-up transformer 48 and electrodes

9 which are connected to the secondary 49 of this transformer by wires 50. The primary 51 of this transformer is connected in series with switch 39 in a circuit which may be traced as follows: from line wire 26, by terminal 24, wires 43 and 52, closed switch 39, wire 53, terminal 54, wire 55, primary 51, wire 56, terminal 57, wire 58 and terminal 25 to line wire 27.

The starting circuit described includes the time switch 15, which usually consists of a bi-metallic member heated by coil 16 and caused to open in a predetermined time, say for example, 90 seconds. If when motor 5 and transformer 48 are simultaneously energized, combustion occurs within the predetermined time, the heating coil 16 of the safety switch will be shunted out to prevent the latter from opening. A suitable thermostat, indicated conventionally at 59 and responsive to burner temperature, actuates the described pairs of contacts 17 and 18, which are initially engaged, as well as a pair of contacts 60, which are initially open. On occurrence of combustion, thermostat 59 first causes contacts 60 to engage, then causes contacts 18 to separate and finally causes contacts 17 to separate. The closure of contacts 60 closes a holding circuit to relay coil 14, which excludes the heating coil 16. This holding circuit may be traced as follows: from the right hand terminal of secondary 19, by wire 28, terminal 29, wire 30, contact 11, blade 10, contact 12, wire 31, terminal 32, wires 33 and 61, closed switch 41, wire 62, closed switch 42, wire 63, engaged contacts 60, wire 64, closed switch 15, wire 36, relay coil 14 and wire 37 to the left hand terminal of secondary 19. The heating coil is first shunted out by the low resistance circuit which includes wire 35, engaged contacts 17, a wire 65, engaged contacts 60 and wire 64, and then cut out of circuit by the subsequent opening of contacts 17. The burner will now operate on a circuit which includes the contacts 60 and which will be quickly broken in the event of failure of combustion by the opening of these contacts.

The closure of switch 40 prepares a circuit, which will cause the heating coil 13 of the accelerating thermostat switch to operate at the proper time, namely, shortly before the end of each run of the burner. This circuit usually includes wires 62 and 66, closed switch 40, wires 67 and 68, terminal 69, wire 70, coil 13 and the blade 10 of the room thermostat switch. However, for the purposes of this invention, such circuit also includes the heating coil 71 of a suitable time switch 72. The described circuit is shunted out, as long as blade 10 engages both contacts 11 and 12 by the following low-resistance path, namely, contact 12, wire 31, terminal 32, wires 33 and 61 and closed switch 41. However, as the demand for heat is nearly satisfied, the blade 10 disengages from contact 12, while maintaining engagement with contact 11, so that the burner now operates on a circuit which includes the heating coils 13 and 71. This latter circuit may be traced as follows: from the right hand terminal of secondary 19, by wire 28, terminal 29, wire 30, contact 11, blade 10, coil 13, wire 70, terminal 69, wire 68, coil 71, wire 67, closed switch 40, wires 66 and 62, closed switch 42, wire 63, engaged contacts 60, wires 64, closed switch 15, wire 36, coil 14 and wire 37 to the left hand terminal of secondary 19. This last-named circuit will come into play in about two minutes before the end of the burner run and the coil 13 will heat blade 10 and cause

it to disengage from contact 11 sooner than it otherwise would.

According to this invention, the disengagement of blade 10 from contact 12 is utilized to set in action a time switch such as 72, regardless of whether or not the heating coil 13 is employed. This time switch may be any commercial form of thermostat-operated switch which will close in a predetermined time, say 90 seconds, after the coil 71 is energized and will open in a like time after coil 71 is deenergized. This time switch controls a circuit to the coil 73 of a second relay, which circuit may be traced as follows: from the right hand terminal of secondary 19 by wire 28 to wire 74, coil 73, wire 75, closed switch 72, wire 76 to wire 37, and up wire 37 to the left hand terminal of the secondary. Relay coil 73, when energized, will close a switch 77, the terminals of which are respectively connected by wires 78 and 79 to wires 52 and 53, whereby an alternate circuit to the primary 51 of the ignition transformer is closed. This alternate circuit will serve to maintain the ignition after the switch 39 opens because of the dropping out of the first relay, when the room thermostat switch opens by the disengagement of its blade 10 from contact 11. When blade 10 leaves contact 11, the circuit to the heating coil 71 of time switch 72 will be broken. However, the circuit to relay coil 73 is not broken by the opening of the room thermostat switch and the dropping out of the relay, which it controls, so that the coil 73 remains energized until switch 72 opens. This occurs in a predetermined time interval, which as described is 90 seconds but which may obviously be varied as desired.

In the event of failure of combustion, the contacts 60 disengage almost immediately and, somewhat later, the contacts 18 re-engage, followed by the re-engagement of the contacts 17. The time between the opening of contacts 60 and the engagement of contacts 17, usually about 60 seconds, affords a scavenging period, after which the burner will start up on the starting circuit previously described. If combustion does not occur within 90 seconds, switch 15 will open to stop the burner and this switch will lock out so that the burner cannot again be started until this switch is manually reset. The stopping of the burner, due to a combustion failure, cannot adversely affect the provisions of this invention for prolongation of the ignition period. Should the burner stop, due to combustion failure, the circuit to heating coil 71 will be broken by the separation of contacts 60 and the subsequent opening of switch 40. If the combustion failure occurs after blade 10 has left contact 12 and thus while coil 71 is energized, the circuit to the coil will be broken and heating of the thermostat of the time switch will be stopped. If the heating has progressed far enough to close switch 72, the ignition will be kept on for a while after the motor 5 stops, which is what the invention provides for normal stops of the burner. If the heating has not progressed to such extent, this switch will not open.

In the diagram of Fig. 2, the parts within the dotted rectangle 80 may all be contained within the usual control box except, of course, the active part of thermostat 59 which usually extends from the back wall of the control box into the stack of the heating apparatus, fired by the oil burner.

The operation will be clear from the foregoing description. The burner motor and the ignition

means are simultaneously started by the relay 14, when actuated by the room thermostat switch, but the opening of the ignition switch by the dropping out of this relay is ineffective to stop the ignition because of the alternate circuit, established by the pulling in of relay 73. This occurs just before the end of each run of the burner by the closing of switch 72. The latter is a time switch which will remain closed until after the burner motor has been stopped. After the lapse of the selected predetermined time, switch 72 will open and cannot again be closed until near the end of the next run of the burner. With the described arrangement the switch 72 must be arranged to close in an interval slightly less than that during which blade 10 is disengaged from contact 12 while still engaged with contact 11, so that the switch will surely close before the blade 10 leaves contact 11 to stop the burner and the first-named interval must be long enough to keep the switch 72 closed until after the burner has stopped.

Another means of securing the prolongation of the ignition is shown in Fig. 3. This is a fragmentary diagram showing only the changes necessary to make in the diagram of Fig. 2. The heating coil 71, time switch 72, coil 73, switch 77 and wires 68, 74 and 76 have been omitted. The heating coil 13 may also be omitted as shown and wire 70 connected directly to blade 10. The switch 77 is replaced by a time switch which includes a brush 81 and a long contact over which the brush may be moved against the force of a spring 83. Brush 81 is fixed to the plunger 84 of a solenoid 85. This plunger carries a piston 86 movable in a dashpot 87 having a large opening 88 covered by a valve 90 which has a very small opening 89. The contact 82 is connected to wire 78 and the brush 81 is connected through the intermediary of plunger 84 and dashpot 87, to wire 79. The solenoid 85 is respectively connected by wires 91 and 92 to wire 37 and terminal 69. The wire 67 from switch 40 is connected to wire 91. On starting, after blade 10 has engaged both contacts 11 and 12 to energize relay coil 14 and cause the closing of switches 38, 39, 40, 41 and 42, the solenoid will be shunted out, the shunt comprising contact 12, wire 31, terminal 32, wires 33 and 61, closed switch 41, wire 66, closed switch 40, and wire 67. When blade 10 leaves contact 12 near the end of the run of the burner, a circuit will be closed to solenoid 85 as follows: from the right hand terminal of secondary 19 by wire 28, terminal 29, wire 30, contact 11, blade 10, wire 70, terminal 69, wire 92, coil 85, wire 91 to wire 37 and up wire 37 to the left hand terminal of the secondary. The solenoid 85 will thus be energized to move plunger 84 and carry brush 81 into engagement with contact 82 and thus, as before, close an alternate circuit to the primary 51 of the ignition transformer. The piston 86 will move freely because valve 90 will open to allow free flow of air through the large hole 88 into the dashpot. The solenoid 85 remains energized and holds the brush 81 engaged near the left hand end of contact 82 until blade 10 leaves contact 11. Then, the previously stressed spring 83 expands and moves the brush 81 to the right along contact 82 but this movement is slowed because valve 89 closes and the only outlet for air is the small hole 89. Thus, the brush 81 will not move off the contact 82 until the lapse of a predetermined time after the circuit to the burner motor is open and the oil-supply pump stops, whereby

any oil on the spark electrodes will be removed by the heat of the spark and the electrodes left dry and clean.

The control system disclosed is of the type which maintains ignition continuously during each run of the burner. This type is generally preferable because of the safety afforded by having ignition always available for re-igniting the oil after a momentary interruption, should one occur. However, the invention is not limited to use with burners having continuous ignition, because if the circuit to the ignition transformer is cut off shortly after ignition occurs, the switch 77 of Fig. 2 or the switch 31, 32 of Fig. 3 will close another circuit to the ignition transformer shortly before the burner stops and maintain such circuit closed for a time after the burner stops. In other words, the operation of the invention in providing for ignition after cessation of the oil supply to the burner nozzle would not be affected by an earlier opening of the ignition switch 39 because of the establishment of an ignition circuit which is entirely independent of this switch.

25 What is claimed is:

In an oil burner, having an atomizing nozzle, electrically-operated means for supplying oil to said nozzle, an electric igniter adjacent said nozzle, energizing circuits one for said means and one for said igniter, and means controlling the opening and closing of both said circuits and including a switch having first and second contacts and a blade movable relatively thereto, a bi-metallic member for moving the said blade in response to variations in temperature in the space to be heated by the burner, said member being operable on falling temperature to move said blade successively into engagement with the first and second contacts in the order named and said blade when engaging both contacts causing both said circuits to close to start the burner, said member on rising temperature being operable to successively move the blade out of engagement with the second and first contacts in the order named and the blade when disengaged from both contacts causing both said circuits to open to stop the burner, an alternate energizing circuit for said igniter, a time-controlled switch in the last-named energizing circuit operable after it has been closed to open in a predetermined time, electrically-operated means for closing said time switch, an energizing circuit for the last-named means including said blade and first contact, and a low resistance circuit including said blade and second contact for shunting out the last-named energizing circuit when the blade engages both said contacts, said blade on rising temperature disengaging first from the second contact to open the shunt circuit and enable the last-named energizing circuit to close the time switch.
